(57) **CLAIM**

The ornamental design for tote bag and insulated cooler combination, as shown and described.

DESCRIPTION

FIG. 1 is a front, left side, top perspective view of a tote bag and insulated cooler combination showing our new design; FIG. 2 is a rear, right side, bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; and, FIG. 9 is front, left side, top perspective exploded view thereof when buckle fasteners are detached permitting the tote bag to be separated from the insulated cooler. The broken lines and the areas within them depict portions of the tote bag and insulated cooler combination that form no part of the claimed design.

1 Claim, 9 Drawing Sheets
